CLAIM

The ornamental design for a telephone receiver cover, as shown and described.

DESCRIPTION

FIG. 1 is a front plan view of the telephone receiver cover of the present invention;

FIG. 2 is a back plan view of the telephone receiver cover of FIG. 1;

FIG. 3 is a left side plan view of the telephone receiver cover of FIG. 1;

FIG. 4 is a right side plan view of the telephone receiver cover of FIG. 1;

FIG. 5 is a top plan view of the telephone receiver cover of FIG. 1; and,

FIG. 6 is a bottom plan view of the telephone receiver cover of FIG. 1.

The broken line showings of a telephone cord throughout the views are for illustrative purposes only and form no part of the claimed design. The grid pattern partially shown in the views is continuous throughout the entire surface of the article.
